(57) CLAIM

The ornamental design for a chest, as shown and described.

DESCRIPTION

FIG. 1 is a left front perspective view of a chest showing my new design;

FIG. 2 is a side elevational view, the opposite side being a mirror image thereof; and,

FIG. 3 is a front elevational view thereof.

The views of the chest not shown form no part of the claimed design. The dashed lines depicting hardware represent environmental elements only and form no part of the claimed design.
